UNITED STATES PATENT OFFICE.

ERNEST HOPE CRUSH, OF BICKLEY, ENGLAND.

GAS-PRODUCER.

1,349,497.

Specification of Letters Patent. Patented Aug. 10, 1920.

Application filed December 29, 1919. Serial No. 348,210.

To all whom it may concern:

Be it known that I, ERNEST HOPE CRUSH, a subject of the King of Great Britain, residing in Bickley, England, have invented certain new and useful Improvements in and Relating to Gas-Producers, of which the following is a specification.

There is a type of gas producer in which the producer shaft consists of an annular water chamber connected at top by short water tubes with a second annular chamber, the whole being inclosed in a casing from which the producer gas is withdrawn. In such a construction the producer gas passes into the casing between the said connecting tubes, thus imparting much of its sensible heat to the water circulating through the tubes from one annular chamber to the other. The upper chambers being provided with the usual appurtenances of a steam boiler, the plant becomes a combined gas and steam generator in which overheating of the walls of the producer is avoided and the gas is partially cooled before it leaves the plant.

By my invention I am enabled to construct an improved producer of the type set forth wherein the main difficulty usual in such type, namely; the collection of dust between the water tubes and the consequent necessity for frequent cleaning, is largely overcome. This object is attained by arranging the tubes in sets spaced apart and placing a baffle plate behind each set of tubes so that the dust-laden gases do not pass directly into the casing between the several tubes but through the said spaces, which are graded in width so that there is a wider passage for gas at that side of the ring of water tubes which is farther from the off-take for gas from the casing. In this manner, not only is deposition of dust between the tubes less liable to occur than in the usual constructions, but less dust is carried away in the gases which, under influence of the baffles, undergoes sharp changes of direction of travel and thereby to deposit the dust which is collected in the casing. The spaces between the sets of tubes also facilitate poking of the fuel in the producer shaft by means of pokers inserted through the top of the casing.

In the accompanying drawings Figure 1 is a vertical section and Fig. 2 a plan, half in section, of a producer constructed according to the invention.

The lower drum A constitutes the shaft

of the producer in known manner, the fuel within its annulus being supported on a grate of any known suitable form. The gas chamber F is a light steel casing K lined with refractory material in the form of fire-clay or similar heat resisting blocks L. It is suitably affixed to the upper drum H and to the annular water chamber A by means of angle irons, while the peripheral socket type of joint in the steel casing at M allows freedom of movement arising from change of temperature between the upper drum H and the lower annular water chamber A.

The annular water chamber A extends somewhat below the gas chamber and is here provided with poke holes B, C, D, E, on radii alternating with those on which are a like number of poke holes N, O, P, Q, in the crown of the gas chamber F.

The inclined tubes G which connect the upper drum H and the annular water chamber A, are so arranged that gaps R, S, T, U, are formed in the otherwise complete ring, those gaps which are nearer the off-take L being narrower than the others. Thus the tubes are in sets and each set is backed by a baffle plate G', so that the gases from the producer can pass only through the said gaps. The latter are respectively in radial register with the poke holes N, O, P, Q.

The upper drum H has an opening W, coaxial with the annular water chamber, for feeding fuel to the producer through a bell and cover delivery box or hopper, which is offset from the axis to afford the necessary clearance for a vertical shaft carrying mechanical pokers, as shown in dotted lines in Fig. 1, when such an arrangement is adopted.

Suitable cleaning doors (not shown) are provided at the lower part J of the gas chamber, for removal of dust.

Having thus described the nature of the said invention and the best means I know of carrying the same into practical effect, I claim:

1. A gas producer comprising a producer shaft, an annular water chamber surrounding the shaft, a second annular water chamber placed above the shaft, a casing surrounding both annular chambers, said casing providing a gas chamber, an off-take for producer gas at one side of the upper part of the gas chamber, upwardly and inwardly inclined tubes connecting the two annular water chambers, said tubes being arranged

in sets spaced apart, said tubes being so arranged that those sets which are adjacent the gas off-take are closer together than those which are more removed from said off-take, a baffle plate behind each set of tubes, said baffle plate being of the same width as the set with which it is in adjacency, the top of said casing being formed with poke holes, said poke holes being in registry with the spaces between the several sets of tubes.

2. A gas producer comprising a producer shaft, an annular water chamber surrounding the shaft, a second annular chamber positioned above the shaft, a casing surrounding the second annular chamber and the upper part of the lower annular chamber to constitute a gas chamber, an off-take for producer gas at one side of the upper part

of said gas-chamber, upwardly and inwardly inclined tubes connecting the two inclined water chambers, said tubes being arranged in sets spaced apart, said sets of tubes which are near the gas off-take being closer together than the sets of tubes farther removed from said off-take, a baffle plate behind each set of tubes, each baffle plate being of a width co-extensive with the set to which it is adjacent, poke holes formed in the upper part of said casing, said poke holes being in registry with the spaces between the sets of tubes, and radially arranged poke holes in the lower part of the first-named annular water chamber.

In testimony whereof I have signed my name to this specification.

ERNEST HOPE CRUSH.
